His Attorney.

UNITED STATES PATENT OFFICE.

RALPH T. CHEESEMAN, OF LYNN, MASSACHUSETTS, ASSIGNOR TO GENERAL ELECTRIC COMPANY, A CORPORATION OF NEW YORK.

CURRENT-REGULATOR FOR INCANDESCENT LAMPS.

1,326,645.

Specification of Letters Patent. Patented Dec. 30, 1919.

Application filed December 14, 1917. Serial No. 207,104.

To all whom it may concern:

Be it known that I, RALPH T. CHEESEMAN, a citizen of the United States, residing at Lynn, county of Essex, State of Massachusetts, have invented certain new and useful Improvements in Current-Regulators for Incandescent Lamps, of which the following is a specification.

My present invention relates to regulating devices and particularly to a device for controlling the current in an incandescent lamp which is used for projection purposes.

When an incandescent lamp is employed in connection with projection apparatus it is important that the current in the lamp be kept as close to the desired operating value as possible. Gas filled tungsten lamps which are suitable for this purpose are designed to operate normally at a high filament temperature and if the current in the lamp is allowed to exceed that desired for normal operation the life of the lamp will be greatly shortened.

One of the objects of my invention is to provide a simple and convenient means for regulating the current in the lamp which can quickly be adjusted by the operator for preventing the current from exceeding the safe operating value.

To accomplish this object, when the lamp is operated by alternating current, I employ an adjustable impedance in the supply circuit and provide a current measuring instrument in the lamp circuit. The operator may quickly tell by reading the measuring instrument when the current in the lamp varies from normal and vary the impedance to adjust it to the desired value.

If the lamp should be turned off with the impedance adjusted to its minimum value the current in the lamp, when started again, might exceed the safe operating value and the life of the lamp would be accordingly shortened.

A second object of my invention is to overcome this disadvantage and provide an arrangement in which it will be impossible for the operator to start the lamp unless the impedance is adjusted to its maximum value. In attaining this object I provide a switch in the supply circuit and place this switch

in such relation to the means for adjusting the impedance that the switch can be operated to close the circuit only when the impedance is adjusted to its maximum value. 55

My invention will best be understood by reference to the following description taken in connection with the accompanying drawing, in which Figure 1 is a view of a casing which contains the regulating apparatus 60 showing the means by which the operator controls the lamp, and Fig. 2 is a view, partly in perspective and partly diagrammatic, showing the relation between the different parts of the apparatus and the supply 65 circuit connections.

As indicated in the drawing, the lamp 1 is supplied with current from the mains 2 through an auto transformer 3 which is designed to furnish the proper operating voltage for the lamp. In series with the primary circuit of the transformer 3 I provide an adjustable impedance comprising an inductive winding 4 and a movable magnetic core 5 within the winding. The position of 70 the core 5 with respect to the winding 4 and the value of the impedance may be varied by turning the handle 6 which is fastened to the shaft 7, the core being operatively connected to this shaft by means of the strap 75 8 which passes over and is attached to the drum 9 which is also fastened to shaft 7. In order to hold the core in the desired position, a friction band 10 is employed surrounding the drum 11 which is mounted on 80 the shaft 7. The lamp may be turned on and off by means of a switch 12 in the primary circuit, which switch may be, as indicated, of the ordinary double push button type. 90

The apparatus is mounted in the casing in such a way that the handle 6 and the push buttons 14 and 15 project from the casing, as indicated in Fig. 1. A notch or opening 16 is provided in the handle 6, this notch being so positioned that when the impedance is a maximum it will come opposite the push button 14 and allow the operator to reach this push button to turn on the lamp. When the handle 6 is at any other 95 position between the points of maximum and minimum impedance it will cover the 100

2
push button 14 and the operator will be unable to operate the switch. It will be impossible for him to turn the lamp off without first turning the handle 6 to the point of maximum impedance as the handle is so positioned as to prevent the push button 14 from projecting beyond the casing, except when it is opposite the notch 16. When the lamp is turned off the push button 14 projects into the opening in the handle and prevents the handle from being turned until the switch is closed. Thus there is no possibility of the operator starting the lamp except when the impedance is at a maximum. The ammeter 17 which is connected in the lamp circuit and mounted on the front of the casing 13 enables the operator to tell at any moment whether the lamp is receiving the proper amount of current.

20 While I have described and illustrated the preferred embodiment of my invention, I do not wish to be limited to the precise structure and circuit arrangement shown as it will be apparent that many modifications 25 therein may be made without departing from the scope of my invention as set forth in the appended claims.

What I claim as new and desire to secure by Letters Patent of the United States, is:—

- 30 1. The combination in an apparatus of the class described of an electric circuit, a switch for closing said circuit having means for the manual operation thereof and means for varying the impedance of said circuit, 35 said means for the manual operation of the switch being so located with respect to said impedance varying means that it can be operated only when the impedance is a maximum.
- 40 2. The combination in an apparatus of the class described of an electric circuit supplied by a source of alternating current, a switch for closing said circuit having means for the manual operation thereof, a reactance in said circuit and means for varying the value of said reactance, said means for the manual operation of the switch being so located with respect to said reactance varying means that it can be operated only when 45 the reactance is a maximum.
3. The combination in an apparatus of the class described of an electric circuit supplied by a source of alternating current, a switch for closing said circuit having means 55 for the manual operation thereof, a reactive winding included in said circuit, a movable core within said winding for varying the reactance thereof and means for moving said core to adjust the reactance to a desired 60 value, said means for the manual operation of the switch being so located with respect to the means for moving said core that it 65 can be operated only when the reactance is a maximum.
- 65 4. The combination in an apparatus of the
- class described of an electric circuit supplied by a source of alternating current, a switch for closing said circuit having means for the manual operation thereof, a reactive 70 winding included in said circuit, a movable core within said winding for varying the reactance thereof and a movable handle for moving said core to adjust the reactance to a desired value, said means for the manual operation of the switch being so located with respect to said handle that it can be operated only when the handle is in a predetermined 75 desired position.
5. The combination in an apparatus of the class described of an electric circuit supplied by a source of alternating current, a push button switch for closing said circuit, a variable reactance included in said circuit, and a handle for adjusting the value of said reactance, said push button being so located with respect to said handle that it can be operated only when the handle is in a predetermined 80 desired position.
6. The combination in an apparatus of the class described of an electric circuit supplied by a source of alternating current, a push button switch for closing said circuit, a variable reactance for adjusting the current in said circuit, and a handle for adjusting the value of said reactance having 85 an opening therein, said push button being so located with respect to said handle that when the reactance is adjusted to any value less than a maximum it will be covered by the handle, and when the reactance is a 90 maximum it will be opposite the opening in the handle.
7. The combination in an apparatus of the class described of an incandescent lamp, a transformer for supplying current to said lamp, a variable reactive winding for adjusting the current supplied to the lamp, a switch for closing a circuit to supply current to the lamp, means for the manual operation of the switch, and means for varying 95 the reactance of said winding to vary the current supplied to the lamp, said means for the manual operation of said switch being so located with respect to the reactance varying means that it can be operated only when 100 the reactance is a maximum.
8. The combination in an apparatus of the class described of an incandescent lamp, a transformer for supplying current to said lamp, a variable reactance for adjusting the 105 current supplied to the lamp, a push button switch for closing a circuit to supply current to the lamp, and a handle for adjusting the value of said reactance, said push button being so located with respect to said handle that it can be operated only when the reactance is a maximum.
9. The combination in an apparatus of the class described of an incandescent lamp, a transformer for supplying current to said 110

lamp, a variable reactance in the primary circuit of said transformer, a push button switch for closing the primary circuit of said transformer to supply current to said lamp, and a handle for adjusting the value of said reactance having an opening therein, said push button being so located with respect to said handle that when the react-

ance is adjusted to any value less than a maximum it will be covered by the handle, 10 and when the reactance is a maximum it will be opposite the opening in the handle.

In witness whereof, I have hereunto set hand this 12th day of December, 1917.

RALPH T. CHEESEMAN.
